UNITED STATES PATENT OFFICE.

BENJAMIN F. GABLE, OF BERKELEY, CALIFORNIA, ASSIGNOR OF ONE-THIRD TO
PACIFIC SANITARY MANUFACTURING COMPANY, OF SAN FRANCISCO, CALI-
FORNIA, A CORPORATION OF CALIFORNIA.

FLUSH VALVE.

1,404,594.

Specification of Letters Patent. Patented Jan. 24, 1922.

Application filed June 20, 1918. Serial No. 240,917.

To all whom it may concern:

Be it known that I, BENJAMIN F. GABLE, a citizen of the United States, and a resident of Berkeley, county of Alameda, and State of California, have invented a new and useful Flush Valve, of which the following is a specification.

My invention relates to valves for the control of the flow from flush tanks.

10 An object of the invention is to provide a valve for use in flush tanks which will remain in the open position, to which it has been moved, during the discharge of water from the tank and will close automatically 15 as soon as the flow ceases.

The invention possesses other features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may 20 25 adopt variations of the preferred form within the scope of my invention as set forth in the claims.

Referring to the drawings:

Figure 1 is a vertical section through the 30 valve mechanism, a portion of the valve stem being broken away to better disclose the parts.

Figure 2 is a horizontal section taken on the line 2—2 of Figure 1.

35 Figure 3 is a detail view of a portion of the mechanism.

Fig. 4 is a vertical sectional view of a portion of the device taken in the plane indicated by the line 4—4 of Fig. 2. Fig. 5 is a 40 perspective of the shaft 21 and offset shoe 22.

My invention consists of a valve to control the flow of water from a flush tank to the toilet bowl and comprises a valve casing 2 adapted to be arranged in the flush tank (not 45 shown). An overflow pipe 3 is connected to an extension 4 of the casing 2 and communicates with the interior of the casing by the passage 6. The upper edge 7 of the casing forms a valve seat and a valve 8 preferably 50 formed of rubber or comparable material faced with metallic washers 9 controls the flow of water from the flush tank through the casing 2 to the bowl. The valve 8 is movable vertically to open or close the passage

through the valve seat and is mounted upon 55 a valve rod or stem 11 which is slidably arranged in the bracket 12 conveniently secured to the overflow pipe 3, and to the bracket 13 secured within the casing 2. The valve stem 11 is raised to open the valve by 60 the usual means which are well known and need not be described herein. The bracket 12 serves as a stop to limit the movement of the valve.

Means are provided for holding the valve 65 8 in the open position to which it has been raised to permit the flow of water through the valve, and this means is operated by the water itself so that upon the emptying of the flush tank and the stoppage of the flow of 70 water therefrom, the valve will close automatically, and the tank again fill. The bracket 13 is conveniently formed of a metallic strip folded to provide an elongated eye 16. The proportions of the bracket are 75 such that the valve rod 11 concentric with the casing 2, lies against the outer wall 17 of the eye, and means are provided within the eye for retaining the stem 11 against the wall at all times so that the stem and valve 80 are not laterally displaceable; and for pressing the stem against the wall with sufficient force during the passage of water through the casing 2 to retain the stem and valve in any position to which they are moved when 85 the valve 8 is raised. A recess 18 is cut in the wall 17 of the bracket to provide a bearing 19 in each wall of the eye and a shaft 21 provided with an offset portion 22 is journaled in these bearings. The offset portion 90 comprises a shoe which bears against the valve stem 11, and when the shaft 21 has been seated in the bearings and the stem 11 inserted between the shoe 22 and the wall 17, lateral displacement of the valve stem is 95 prevented and clockwise rotation of the shaft 21, as viewed in Figure 1, will cause the shoe 22 to clamp the stem 11 against the wall 17 of the eye. It is to be noted that the axis of rotation of the shaft 21 lies between 100 the wall 17 on one side and the shoe on the other side, so that downward pressure on the valve stem tends to disengage the shoe therefrom and does not tend to tighten the shoe pressure, such as would be the case if the 105 shoe was between the axis and the wall. Consequently there can be no possible tendency for the shoe to jam against the stem and pre-

vent the proper closing of the valve when pressure on the shoe is released.

The shaft 21 is turned to actuate the shoe by means of a plate 24 secured rigidly thereby and extending outwardly and preferably downwardly into the passage 26 through which the water flows from the flush tank. The plate is provided with a recess 27 in which the eye of the bracket and the stem 11 lie without touching. Preferably the bracket 13 is removably secured to the casing by means of oppositely disposed flanges 28 adapted to be engaged behind the bar 29 secured to the wall of the casing and spaced therefrom. The bar is provided with a notch adapted to receive the portion 31 of the bracket.

The parts are assembled by first passing the shaft 21 through the recess 18 to a seat on the bearings 19. The bracket with shaft and plate in place is next engaged with the bar 29, after which the lower portion of the valve stem with valve attached is inserted between the shoe and wall 17. The upper portion of the valve stem and the bracket 12 are then added.

Operation: Upward movement of the valve stem, raises the valve 8 and permits water from the flush tank to flow through the casing 2. No resistance to the upward movement of the valve stem is offered by the shoe since the weight of the plate 24 is insignificant and the stem therefore slides upwardly freely, tending to throw the shoe outwardly or disengage it from the stem. The instant the outgoing water strikes the plate 24, it is moved a small amount downwardly about the axis of the shaft, and the shoe is pressed against the stem 11, clamping it against the wall 17. The plate and shoe thus act as a lever and the pressure of the shoe on the stem is maintained as long as the water impinges upon the plate 24. As soon as the stream has been reduced so

that no water strikes the plate, the weight 45 of the stem and valve causes the latter to fall upon the valve seat so that further discharge from the tank is prevented until the valve is again raised. No jamming of the stem between shoe and wall 17 is possible 50 since movement of the stem 11 in either direction tends to move the shoe away from the wall, and it is only by the impact of water upon the plate 24 that the shoe is pressed against the stem. 55

I claim:

1. A flush valve comprising a casing, a seat formed in said casing, a valve arranged on said seat, a stem on said valve, a bracket 60 removably attached to the inside wall of said casing and having an eye therein through which said stem passes, a shoe pivotally arranged in said eye in engagement with said stem, and a plate attached to said shoe and adapted to be moved by the water passing 65 through said valve to clamp said stem against the wall of said eye, the axis of said pivot and the wall of said eye lying on the same side of said shoe.

2. In a flush valve, a valve seat, a valve 70 adapted to engage said seat, a bracket arranged below said valve seat, a stem on said valve passing through and engaging said bracket, a shaft pivotally mounted in said bracket on an axis intercepting said stem, a 75 shoe formed on said shaft by offsetting the center thereof and adapted to engage the side of said stem opposite the side engaged by said bracket, and a plate fixed on said shaft and disposed on the opposite side of 80 said stem from said shoe.

In testimony whereof, I have hereunto set my hand at San Francisco, California, this 12th day of June 1918.

BENJAMIN F. GABLE.

In presence of—
C. S. EVANS.
